UNITED STATES PATENT OFFICE.

GEORGE W. HUEY, OF WILKINSBURG, AND HENRY D. JAMES, OF EDGEWOOD PARK, PENNSYLVANIA, ASSIGNEES TO WESTINGHOUSE ELECTRIC AND MANUFACTURING COMPANY, A CORPORATION OF PENNSYLVANIA.

MAGNET CONTACTOR.

Application filed May 4, 1920. Serial No. 378,792.

Our invention relates to switches and switchboard panels and it relates particularly to switching devices for relatively high-voltage circuits.

- 5 The object of our invention is to provide a switching device, of the above-designated character, which may be constructed of such standard parts as are employed in ordinary insulating and switchboard constructions and 10 in such manner as to provide a structure that may be adapted to a series of switches designed for a large range of voltage values by merely changing certain minor portions of the apparatus.
- 15 A further object of our invention is to provide a switchboard panel which may be constructed of structural iron and the like and the design of which is readily adaptable to switches of various capacities and to 20 switches of different voltages.

Heretofore, it has been customary, in the construction of panels of the above-indicated character, to employ base members of insulating material on which the various 25 switching devices are mounted.

In accordance with our invention, we provide a panel constructed of structural iron on which the various switch members are mounted and from which they are insulated 30 by means of standard insulating structures of the kinds employed in various other forms of apparatus. Furthermore, our structure is of such flexible design that it may be arranged to accommodate any one 35 of a relatively large series of switch designs having different numbers of contactors and arranged for wide ranges of voltage and current values.

Fig. 1 of the accompanying drawing is a 40 front elevational view of a switching device constructed in accordance with our invention; and Fig. 2 is a side elevational view of the device shown in Fig. 1.

The drawings illustrate a panel 1, or 45 frame, of structural iron on which a pair of auxiliary panels 2 and 3 are mounted and insulated therefrom by insulators 4 and 5. A stationary switch contact member 6 is mounted on each of the auxiliary panels 50 2 and 3, and a movable contact member 7 is actuated into and out of engagement with each of the stationary contact members 6 by means of an actuating device 8.

The structural framework 1 comprises a

pair of upright channel members 9 and 10 55 that are mounted on a base member 11 of channel shape and are connected by a top angle iron 12 and by an intermediate plate 13.

The framework 1 should be of a construction that will permit of co-ordination of a series of like panel members in such manner as to compose a complete switchboard.

Each of the auxiliary panels 2 and 3 is 65 of insulating material and the panels are mounted on insulators 4 and 5 in order to effectively insulate the electrical devices that are mounted on the auxiliary panels 70 from the structural framework and to dispose the panels in spaced relation upon the framework 1.

An arc-blowout shield 14, which is mounted on each of the panels 2 and 3, comprises a blowout coil 15 and magnetic side-plate 75 members 16 therefor. One terminal of each of the blowout coils 15 is connected to a terminal member 17 by means of a bolt 18 and a conductor 19. The remaining terminal of each of the coils 15 is connected to the 80 corresponding stationary contact member 6.

Each of the stationary contact members 6 is secured in place by means of a series of bolts 20 that serve, also, to secure the auxiliary panels 2 and 3 to the insulators 5. 85

The movable portion of each of the switch mechanisms embodies a contact member 7 that is pivotally mounted on a bracket member 24 by means of a pin 22 and is yieldingly held in position by a spring 23, in a 90 familiar manner. The contact member 7 is electrically connected to a terminal member 25 through a bolt 26 and a flexible conductor 27. The several bolts 26 extend through insulators 28 that are respectively mounted 95 on the channel members 9 and 10. The bracket members 24 are mounted on rods 29 of insulating material, such, for example, as micarta rods, which are clamped to a transverse rod 30 by means of respective 100 sets of clamping jaws 31.

The actuating mechanism 8 comprises a core member 32, two coils 33, which are mounted on the respective legs of the core member 32, and an armature member 34. 105 The armature member 34 is supported by an arm 35 that is clamped to the transverse rod 30. Bearing members 36 and 37, which

are mounted on a base member 38, constitute supports for the transverse rod 30. The base member 38 supports the core member 32 of the electromagnet.

5. An additional panel 39, preferably of insulating material, is mounted on the lugs 40 of the base member 38 and is secured to the frame 1 by means of the bolts 41.

10. The panel 39 constitutes an insulating base on which any auxiliary apparatus, such, for instance, as relays, meters and the like, may be mounted in order to complete a control unit that embodies the relatively high-voltage switching members.

15. The frame 1 may be maintained in an upright position by a depending leg 42 that is connected, at one end, to the cross member 13 and, at its other end, to the floor.

20. The particular utility of the switching device hereinbefore described will be appreciated when it is pointed out that the insulating members 4 and 5 are of a type frequently employed for other purposes in electrical installations and which may be procured for a relatively large series of voltage values, and that the voltage for which the switch is to be used determines the type of insulator support to be employed.

25. It will be understood that, by a mere change of the insulating members 4, 5 and 28 and by the use of insulating rods 29 of varying lengths, a switching device may be provided for any desired voltage without employing other than a standard series of 30. panel members or frame members. Another item of importance is the fact that the actuating mechanism 8 is not insulated from the frame work and, therefore, is not subjected to relatively large values of voltage, as is 35. the case in such structures as have heretofore been provided.

40. The required change in the length of the insulating rods 29 may be compensated for by moving the base member 38 upwardly or downwardly in accordance with the position necessary to provide accurate coaction between the movable contact members 7 and the stationary contact members 6.

45. We claim as our invention:

50. 1. A switching device comprising a fabricated metal main panel, an auxiliary insulating panel, insulating members for sup-

porting the auxiliary panel in spaced relation to said main panel, a switch member mounted on said auxiliary panel, a movable contact member insulated from and mounted on the main panel for coacting with said switch member, and an actuating device for operating said contact member mounted on said main panel.

55. 2. A switching device comprising a main panel of structural iron, an actuating device mounted on said main panel, a plurality of auxiliary panels, insulating members for mounting said auxiliary panels on said main panel, a stationary contact member mounted on each of said auxiliary panels, a movable contact member cooperating with each of said stationary contact members, and an arm of insulating material for connecting 60. each of said movable contact members to said actuating device.

65. 3. A switching device comprising a main supporting panel, a movable switch member adjustably mounted upon the main panel, a terminal device fixed to the main panel and flexibly connected to the switch arm, a second terminal device on the main panel, an auxiliary insulating panel supported in spaced relation to the main panel by the 70. second terminal device and a switch contact member adapted to be engaged by the switch member and connected to the second terminal device.

75. 4. A switching device comprising a main metal supporting panel, an auxiliary insulating panel, insulator members for supporting the auxiliary panel in spaced relation to the main panel, a switch contact member mounted on the auxiliary panel, metal switch mechanism mounted directly upon the main panel, an insulated switch arm rotatably mounted on the switch mechanism and provided with a contact member for engaging the said switch contact member and a flexible conductor supported upon and insulated from the main panel and connected to the 80. last said contact member.

85. In testimony whereof, we have hereunto subscribed our names this 19th day of April, 100. 1920.

GEORGE W. HUEY.
HENRY D. JAMES.
